FIG. 3

2,874,767

ROTARY ATOMIZING BURNER APPARATUS FOR LIQUID FUEL

Hendrik N. F. Verloop, Amsterdam, Netherlands

Application August 2, 1955, Serial No. 525,996

5 Claims. (Cl. 158—77)

The invention relates to a rotary atomizing burner apparatus for liquid fuel, such as oil, of the kind comprising a substantially cup-shaped rotary atomizer member which is connected with a fuel supply means and which is coaxially surrounded by a stationary air nozzle sleeve, the axially extending annular space comprised between the atomizer member and the sleeve communicating with the pressure side of a rotary blower for forcing air through this annular space outwardly towards the burner mouth. In this known type of burner the air stream in escaping from the annular space inside the air nozzle sleeve flows past the edge of the rotating atomizer member and takes along the drops of fuel, flung away from this edge, in finely dispersed form.

It has been found that the atomization of the fuel and the dispersion of the fuel particles in the air is greatly improved when the escaping air stream in addition to its axial velocity has imparted to it a rotational movement in opposition to the direction of rotation of the atomizer member. Any such rotational movement of the air stream will, however, be counteracted by the atomizer member rotating in the opposite direction when the air passing through the relative narrow annular space between the air nozzle sleeve and this member is made to flow for a long stretch along the outer wall thereof. At lower air speeds this braking effect of the atomizer member could easily become so pronounced as to completely suppress the whirling motion originally imparted to the air.

It is accordingly an object of the invention to solve this problem and to provide a rotary atomizing burner apparatus of the afore-mentioned kind in which a strong whirling motion in opposition to the rotational direction of the atomizer member can be imparted to the air stream escaping from the nozzle mouth. Another important object of the invention is to provide novel means for regulating within wide limits the ratio between the rotational velocity and the axial velocity of the air stream so as to make it possible to effectively control the shape of the burner flame and to adapt this flame to the form and dimensions of the combustion chamber.

According to the invention, the air delivered by the blower is forced into the annular space enclosed between the atomizer member and the air nozzle sleeve through a number of tangentially directed inlet ports provided in the wall of this sleeve which inlet ports preferably have the form of slots axially extending in the sleeve wall. The air thus enters the annular space sideways and in a tangential direction, passing through the slots in the sleeve wall directly opposite the side wall of the atomizer member.

Thereby the air in moving towards the burner mouth is only for a short stretch subjected to the opposing rotational action of the atomizer member so that its initial whirling motion in the sleeve is but little weakened.

The air inlet ports opening tangentially in the annular space provide sharply pronounced tangential air streams which on entering the air nozzle sleeve are forced to

follow the curved inner sleeve wall whereby a strong whirling motion is obtained.

According to a preferred embodiment of the invention, in addition to the tangentially directed inlet ports the wall of the air nozzle sleeve is further provided with radially directed inlet ports likewise preferably having the form of axially extending slots, a regulating valve sleeve being closely mounted on the air nozzle sleeve for rotary sliding movement thereabout which valve sleeve is provided with air passage openings adapted to cooperate with the respective inlet ports in the air nozzle sleeve and being shaped and positional in such a way that when by a turning movement of the valve sleeve the tangential inlet ports of the air nozzle sleeve are gradually closed, the radial inlet ports of the latter are gradually opened, and vice versa. It is thus possible to mix the radial and tangential air streams entering the air nozzle sleeve through the respective ports in any desired ratio whereby an accurate adjustment of the shape of the flame within wide limits can be obtained.

These and other features of the novel arrangement will appear more fully from the following description in conjunction with the accompanying drawings which illustrates by way of example an embodiment of the invention. In the drawing

Figure 1 is an axial section of the apparatus on the line I—I of Figure 2;

Figure 2 is an end view of the apparatus, partly a section on the line II—II of Figure 1 with the forward wall of the casing removed; and

Figure 3 is a detail on an enlarged scale.

The apparatus illustrated in the drawing comprises a hollow shaft 1 adapted to be driven by an electric motor (not shown) and carrying on its outer end a cup-shaped atomizer member 2 to which fuel oil can be fed in the known manner from a supply system (not shown) through the bore of the hollow shaft 1 and a pipe 3 communicating with this bore.

The shaft 1 further carries a fan 4 of a blower, the hub of the fan being locked between a ring 5 on the shaft 1 on the one hand and a threaded sleeve member 6 screwed on the threaded shaft end on the other hand. This sleeve member projects forwardly and threadedly engages the base portion of the cup 2. The shaft 1 is mounted by a ball bearing 7 for rotation in a casing part 8 of the blower.

The blower casing consists of two parts bolted together, to wit: the rear part 8 having an air intake opening 9 and accommodating the fan 4, and the forward part 10 of substantially conical shape and comprising a flat baffle plate 11 which extends radially directly in front of the fan 4 and has substantially the same radius as the latter. The two parts 8 and 10 of the blower casing are in communication with one another through the annular opening 12 formed between the edge of the baffle plate 11 and the rounded inner wall where the casing parts meet. The air forced radially outwardly by the fan 5 is thus made to pass around the edge of the baffle plate 11 and thence moves again inwardly towards the cup 2 along arc-shaped vanes 13 fixedly mounted inside the casing part 10 between the baffle plate and the forward wall thereof.

The baffle plate 11 has a threaded hub portion 11a coaxial with the shaft 1 which carries the threaded inner portion of an air nozzle sleeve 14 of cylindrical form. The sleeve 14 coaxially surrounds the atomizer cup 2 but is spaced therefrom so as to form an axially extending annular space 15 between its inner wall and the outer wall of the cup 2. This space on account of the forwardly flaring shape of the cup 2 gradually narrows towards the annular burner mouth comprised between the edges of the sleeve 14 and the cup 2. The front wall of the

casing part 10 has a cylindrical rim portion 10a closely fitting around the sleeve 14 but allowing the latter to be screwed further inwardly or outwardly on the hub portion 11a for axial adjustment of its forward edge with respect to the edge of the cup 2. The sleeve can be locked in any desired position by means of a removable stop 28 screwed to the outside of the casing part 10 and projecting with its forward end between any two of a number of equally spaced ribs 29 provided in a circle on the outer wall of the sleeve 14.

The air nozzle sleeve 14 is provided with air inlet ports 16 and 17 which extend axially in the form of narrow slots opposite the side wall of the cup 2. The four ports 16 are tangentially directed with respect to the annular space 15 whereas the four narrower ports 17 are radially directed. On the outside of the sleeve the openings to the ports 16 and 17 are situated two and two directly adjacent one another. The forward and rear walls of the ports are inclined towards the burner mouth as is shown in Figure 1 for one of the ports 16.

Closely surrounding the sleeve 14 there has been provided a regulating valve sleeve 18 which can be turned about the sleeve 14 but is held against axial displacement between the baffle plate 11 and the shoulder of the rim portion 10a. The valve sleeve 18 has four slots 19 which on the inside correspond in size to the openings to the slots 16 and are equally spaced as the latter but have radially outwardly flaring side walls to facilitate the inflow of air. The valve sleeve 18 carries a fork 20 engaging a fork pin 21 on an arm 22 which is fixed to a shaft 23 rotatably mounted in the blower casing. One end of the shaft 23 projects outside the casing and has fixed thereon a disc 24 provided with a mark which lies opposite a fixed scale 25 (see also Figure 3). By means of a key applied to a nut 26 fixed on the shaft 23 this shaft and thereby the valve sleeve 18 can be adjusted when the burner is in operation and the relative position of the valve sleeve can be read on the scale 25. By means of a locking bolt 27 engaging the disc 24 the valve sleeve can be fixed in any desired position.

In the position of the valve sleeve shown in Figure 1, the tangential ports 16 are completely open whereas the radial ports 17 are closed. On rotation of the shaft 1 in the direction of the arrow 30 (Figure 2) the flow of air derived from the fan 4 is deflected by the curved vanes 13 and directed towards the tangential ports 16 whereby the air streams entering the space 15 in addition to their axial velocity obtain a substantial rotational movement in the direction of the arrow 31, i. e. in opposition to the rotational direction of the cup 2. On account of the shape and position of the ports 19 with respect to the cup wall, the air flow on its way from the ports to the burner mouth is but little influenced by the rotation of the cup.

As a result the air leaves the burner mouth at the forward end of the space 15 with a strong whirling motion resulting in an excellent combustion and a relatively broad flame.

When the valve sleeve 18 is thereupon turned in anti-clockwise direction into the position indicated with dotted lines in Figure 2, the tangential ports 16 are partly closed and simultaneously the radial ports 17 partly opened whereby the whirling motion is correspondingly diminished and a longer flame obtained.

By further turning the valve sleeve in anti-clockwise direction it can be adjusted to a position in which the air leaves the burner mouth practically without any whirling motion at all.

In this way the shape of the flame can be accurately adapted to the required conditions and the form of the combustion chamber which adjustment can moreover be performed when the burner is in operation so that its effect on the flame can be directly checked. By axial adjustment of the sleeve 14 the shape of the flame can be further modified.

It will be clear that within the scope of the invention various modifications of the described embodiment thereof may be resorted to. For instance, the ports 16 and 17 can be placed further apart in which case the slots 19 of the valve sleeve 18 have to be correspondingly wider so as to cover the distance between the corresponding side edges of two adjacent ports 16 and 17; alternately, the valve sleeve can also be provided with a separate slot for each port 16 and 17 if only these slots are so positioned that when by a turning movement of the valve sleeve the slots 16 are gradually closed, the slots 17 are simultaneously gradually opened, or vice versa.

What is claimed is:

1. In a rotary atomizing burner apparatus for liquid fuel, a substantially cup-shaped rotary atomizer member, means for feeding fuel to said atomizer member, a stationary air nozzle sleeve member coaxially surrounding said atomizer member and spaced therefrom to form an axially extending annular space between said atomizer member and sleeve member, said sleeve member being provided with a plurality of circumferentially-spaced air inlet ports directed tangentially with respect to said annular space and a plurality of circumferentially-spaced radially directed air inlet ports disposed in the spaces between said first-named inlet ports to provide a plurality of pairs of ports with each pair consisting of a tangentially-directed inlet port and a radially-directed inlet port, a regulating valve sleeve closely mounted on said air nozzle sleeve for rotary sliding movement on said air nozzle sleeve in both directions, said valve sleeve being provided with air passage openings adapted to cooperate with the respective pairs of inlet ports of said sleeve member and shaped and positioned in such a way that when upon rotation of the valve sleeve about the nozzle sleeve the tangential inlet ports of the sleeve member are gradually closed and the radial inlet ports of the latter are gradually opened, and vice versa, and blower means for forcing air into said annular space through the air passage openings of said valve sleeve and the air inlet ports of said sleeve member.

2. A rotary atomizing burner apparatus for liquid fuel, comprising a substantially cup-shaped rotary atomizer member adapted to be driven for rotation in one direction, means for feeding fuel to said atomizer member, a stationary air nozzle sleeve member mounted coaxially about said atomizer member and spaced therefrom to provide an axially extending annular space between said atomizer member and sleeve member terminating in an annular burner mouth between the forward rims of said two members, said sleeve member being provided with a plurality of circumferentially-spaced air inlet ports opening tangentially into said annular space in a direction against the direction of rotation of said atomizer member and with a plurality of circumferentially-spaced radially directed ports disposed in the spaces between said first-named inlet ports to provide a plurality of pairs of ports with each pair consisting of a tangentially-directed inlet port and a radially-directed inlet port, said ports extending axially in the form of slots, a regulating valve sleeve closely surrounding said air nozzle sleeve member for rotary sliding movement on said air nozzle sleeve in both directions, means for the manual adjustment of the angular position of said valve sleeve with respect to said air nozzle sleeve member, said valve sleeve being provided with air passage openings in the form of axially extending slots adapted to cooperate with the respective pairs of inlet ports of said sleeve member and shaped and positioned in such a way that when upon rotation of the valve sleeve the tangential inlet ports of the sleeve member are gradually closed, the radial inlet ports of the latter are gradually opened, and vice versa, and blower means for forcing air into said annular space through the air passage openings of said valve sleeve and the air inlet ports of said sleeve member.

3. A rotary atomizing burner apparatus according to

claim 2 in which the side walls of the air passage openings in said valve sleeve diverge in a radially outward direction with respect to the axis of said sleeve.

4. A rotary atomizing burner apparatus according to claim 2 in which in relation to the outer wall of the air nozzle sleeve member a radially directed inlet port is situated directly adjacent each tangentially directed inlet port and in which said valve sleeve has a single air passage opening for each pair of adjacent tangential and radial inlet ports, the width of said air passage opening substantially corresponding to the width of the tangential inlet port.

5. A rotary atomizing burner apparatus for liquid fuel, comprising a casing, a shaft mounted in said casing for rotation in one direction and having an axial bore, a substantially cup-shaped atomizer member fixedly mounted on the forward end of said shaft, means for feeding fuel to said atomizer member through the bore in said shaft, a fan inside said casing mounted on said shaft to the rear of said atomizer member, an air nozzle sleeve mounted in said casing coaxially about said atomizer member and spaced therefrom to enclose an axially extending annular space between its inner wall and the atomizer member terminating in an annular burner mouth between the forward rims of said two members, said sleeve member being provided with a plurality of circumferentially-spaced air inlet ports opening tangentially into said annular space in a direction against the direction of rotation of said atomizer member and with a plurality of circumferentially-spaced radially directed air inlet ports disposed in the spaces between said first-named inlet ports to provide a plurality of pairs of ports with each pair consisting of a tangentially-directed inlet port and a radially-directed inlet port, said tangentially and radially directed ports both extending axially in the form of slots, a regulating valve sleeve mounted in said casing and closely sur-

rounding said air nozzle sleeve member for rotary sliding movement on said air nozzle sleeve in both directions, regulating means adapted to be manually operated from the outside of said casing for the adjustment of the angular position of said valve sleeve about said air nozzle sleeve member, said valve sleeve being provided with air passage openings in the form of axially extending slots adapted to cooperate with the respective pairs of radially and tangentially directed inlet ports of said sleeve member and shaped and positioned in such a way that when upon rotation of the valve sleeve the tangential inlet ports of the sleeve member are gradually closed, the radial inlet ports of the latter are gradually and correspondingly opened, and vice versa, and means comprising a baffle plate and vanes inside said casing for deflecting the air flow forced in a direction away from the shaft by said fan inwardly again towards the openings of said valve sleeve.
